United States Patent Office

Des. 181,780
Patented Dec. 24, 1957

181,780

COFFEE POT OR SIMILAR ARTICLE

Mary W. Burns, Wilmington, Del.

Application May 9, 1956, Serial No. 41,406

Term of patent 14 years

(Cl. D44—26)

Fig. 3.

I claim:

The ornamental design for a coffee pot or similar article, substantially as shown.
